Primary Examiner — Patricia A Palasik*(74) Attorney, Agent, or Firm* — Gary K. Price(57) **CLAIM**

The ornamental design of an RPM sensor for an automated clutch system, as shown and described.

DESCRIPTION

FIG. 1 is a lower perspective view of an RPM sensor for an automated clutch system showing my new design.

FIG. 2 is a left side view thereof;

FIG. 3 is a front end view thereof;

FIG. 4 is a right side view thereof;

FIG. 5 is a back end view thereof;

FIG. 6 is a bottom view thereof;

FIG. 7 is a top view thereof; and,

FIG. 8 is a side sectional view thereof, taken from line 8-8 in FIG. 6.
